UNITED STATES PATENT OFFICE.

JOHN A. BROWNE, OF SAVANNAH, GEORGIA.

HAWSER-CONVEYER.

1,295,847.

Specification of Letters Patent.

Patented Mar. 4, 1919.

Application filed August 19, 1918. Serial No. 250,571.

To all whom it may concern:

Be it known that I, JOHN A. BROWNE, a citizen of the United States, residing at Savannah, in the county of Chatham and State of Georgia, have invented a new and useful Hawser-Conveyer, of which the following is a specification.

This invention relates to a hawser conveyer particularly designed for use in putting out supplemental towing hawsers from a tug or other towing boat to a barge or the like, or from one barge to another. Owing to the excessive cost of a towing hawser it is the practice to utilize only one hawser for connecting a barge or the like with the boat used for towing it but on the approach of heavy weather it is often desirable, especially where an old and worn hawser is in use, to put out a supplemental hawser. Because of the weight of a hawser, it has heretofore been very difficult to get it from one boat to another while in motion and because of this condition many disasters resulting from the parting of a hawser have occurred.

One of the objects of the present invention is to provide a conveyer which is simple and compact in construction and which, after being placed on the tow line or hawser already in position and fastened to the second hawser, can be caused to travel along the tow line, there being drags of novel form connected to the conveyer and supported in the water so that, as the boats move forward, the relative positions of the two hawsers will gradually change until the second or supplemental hawser arrives within reach of a person on the towed boat whereupon it can be attached and used to relieve the first hawser.

Another object is to provide drag devices of novel form which can be lowered into the water without producing a sudden jerk which might bend or break some portion of the apparatus, it being possible also to gradually lift said devices from the water after they have served their purpose.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of the parts without departing from the spirit or sacrificing any of the advantages of the invention as set forth in the appended claims.

In the accompanying drawings the preferred form of the invention has been shown.

In said drawings—

Figure 1 is a perspective view of the stern portion of a boat and showing the apparatus in position thereon just as the conveyer is starting to travel toward the towed boat.

Fig. 2 is an elevation of the conveyer.

Fig. 3 is a section on line 3—3, Fig. 2.

Referring to the figures by characters of reference, 1 designates a frame having a removable side 2 which can be held in place in any manner desired. For example threaded studs 3 can be extended from the top and bottom of the frame and project loosely through the ends of the said side 2, the terminals of the studs being engaged by wing nuts 4. A central opening 5 is provided in the top and bottom of the frame and additional openings 6 are formed in the sides of the frame near the upper and lower ends thereof. These latter openings receive trunnions or gudgeons 7 extending from rollers 8 and 9 located adjacent the upper and lower ends of the frame, the roller 8 being concave, as shown, while the roller 9 is provided with an annular groove 10 at the center thereof.

A yoke 12 is adapted to straddle the front face of either end of the frame and has openings 13 designed to register with the opening 5 in said end so as to receive a pin 14. A cotter 15 extends through the inner end of the pin 14 to prevent withdrawal of the pin from the openings and an eye 16 is located at the outer end of the pin for the purpose hereinafter set forth. By removing the cotter 15 the pin 14 can be withdrawn, thereby releasing the yoke 12 which can thus be transferred to the other end of the frame 1 and secured in the same manner heretofore described.

One arm of the yoke 12 extends through the frame 1 and terminates in an ear 17 extending at right angles thereto. This arm is adapted to support a bar 18 which fits snugly between the ear 17 and the sides of frame 1, the ends of the bar projecting laterally beyond the sides of the frame 1 as shown. A set screw 19 may be extended through the ear 17 and engage the bar to bind against it and hold it against displacement upwardly or longitudinally relative to the frame.

Secured to the ends of the bar 18 are drags 20 each of which is secured to the open end of a flexible bag or bucket 21 constitut-

- ing a drag. To the bottom or closed end of each drag is attached a haul line 22 which is likewise fastened to one end of the bar 18. 65
- Under ordinary conditions the conveyer, 5 consisting of the frame 1 and the parts therein, the bar 18 and the drags 21 and their lines are stowed away and a single hawser H is used for towing. A supplemental hawser H' is also stowed away for emergency purposes. 10
- When it is desired to pay out the supplemental hawser the side 2 of frame 1 is removed and said frame is suspended over the stern of the towing boat B and placed in position with the roller 8 resting on the 15 hawser H. The side 2 is then replaced and fastened and the hawser H' is lashed to the eye 16. Yoke 12 is of course located at the bottom of the frame and supports the bar 18. After the parts have been positioned as 20 described the drags 21 are lowered by means of the lines 22 so that they will hang with their open ends lowermost, and these drags will thus gradually enter the water and fill and will gradually assume their filled and substantially horizontal positions. As the boat 25 B is moving the water will tend to hold back the drags 21 with the result that while the frame 1 will be retarded in its forward movement, the hawser H will pull forwardly 30 through the frame and the hawser H' will be paid out from the boat B. This action will continue until the frame reaches the towed boat whereupon a person thereon attaches the hawser H' to the boat or barge, 35 detaches it from the eye 16, pulls upwardly on the lines 22 to invert, empty and raise the drags 21, and then removes the frame 1 from the hawser H. If two or more barges are 40 in tow, the frame can be taken to the stern of the first barge after being received in the manner described, and can be used for carrying a hawser from the first to the second barge. By having a light line attached to the conveyer frame the frame can be pulled back to the towing boat after the supplemental hawser has been carried over and secured. 45
- The roller 8 is of course designed for use in connection with an ordinary hawser. If, 50 however, a wire cable is used for towing, the frame is inverted to bring the roller 9 uppermost and the groove 10 will receive the cable. The yoke 12 can obviously be changed from one end to the other when the frame is inverted. 55
- What is claimed is:—
1. A hawser conveyer including a roller carrying structure adapted to engage and travel along a hawser, and a drag connected to said structure. 60
  2. A hawser conveyer including a roller carrying structure adapted to be supported by and to travel along a hawser, means for attaching a supplemental hawser to said structure, and a drag connected to the structure. 65
  3. A hawser conveyer including a frame, a roller therein, and a drag bucket connected to the frame. 70
  4. A hawser conveyer including a frame adapted to open at one side, a roller within the frame, and a drag bucket connected to the frame. 75
  5. A hawser conveyer including a frame, a roller therein, a bar connected to the frame, and a drag bucket connected to each end of the bar. 80
  6. A hawser conveyer including a frame, a roller therein, a bar connected to the frame, a tow line and a haul line connected to each end of the bar, and a flexible drag bucket having its open end connected to the tow line and its bottom or closed end connected to the haul line. 85
  7. A hawser conveyer including a structure adapted to be supported by and to move along a hawser, means for attaching a hawser thereto, a tow line and a haul line connected to the structure, and a drag bucket having its open end connected to the tow line and its closed end connected to the haul line. 90
  8. A hawser conveyer including a reversible frame, spaced rollers therein, said frame having a removable side, and a drag connected to the frame. 95
  9. A hawser conveyer including a frame, having a removable side, a yoke connected to one end of the frame, a transverse bar connected to the yoke and bearing against the sides of the frame, and a drag connected to each end of the bar. 100
  10. A hawser conveyer including a frame having a removable side, a transversely extending bar bearing against the sides of the frame, means for detachably connecting the bar to the frame, a tow line and a haul line connected to each end of the bar, and a drag bucket having its open end connected to one tow line and its closed end connected to one haul line. 105
  11. A hawser conveyer including a structure adapted to engage and travel along a hawser, and a drag connected to said structure. 110
  12. A hawser conveyer including a frame adapted to open to receive and be supported by a hawser, and a drag connected to said frame. 115

In testimony that I claim the foregoing as my own, I have hereto affixed my signature 120 in the presence of two witnesses.

JOHN A. BROWNE.
